FIG. 2

FIG. 1

FIG. 4

FIG. 3

FIG. 1 is a perspective view of our new design for a combined public telephone enclosure and support wherein the support is free standing and includes a walk-in enclosure;

FIG. 2 is a rear view of the support;

FIG. 3 is a front view of the support; and

FIG. 4 is a side view of the support, the opposite side being essentially a mirror image thereof.

This application is a division of our copending application, Ser. No. 260,064, filed June 5, 1972.

We claim:

The ornamental design for a combined public telephone enclosure and support, substantially as shown and described.
